14 Claims. (Cl. 141—130)

ABSTRACT OF THE DISCLOSURE

Fraction-collecting apparatus provided with a support to hold a specimen-containing tube vertically, the bottom of the tube being capable of being punctured without fracturing, a conduit having a needle for puncturing the bottom of the tube and supported in vertical alignment with the axis of the tube, a backing member engageable with the open end of the tube, and means to effect relative vertical movement between the needle and the container to effect the puncturing of the tube. The apparatus also including means to refrigerate the tube and to enable it to be used with tubes of different dimensions. The apparatus also provides backing members that are closures, the closures also having conduits.

The present invention relates to apparatus for use in collecting fractions from a tubular container in which a specimen liquid has been separated into gradients.

Testing procedures with gradients commonly require a number of tests on each gradient, each test being based on small precise amounts, a few drops, for example. The withdrawal of such amounts through the open end of the tubes is difficult to perform and usually results in some mixing of the gradients which is, of course, objectionable.

The problem has been recognized for some time and special tubes have been proposed having an axial passage in their bottom, closed by a seal that could be punctured by the needle of a hypodermic or like syringe by which small amounts could then be withdrawn. Such tubes, were, of course, relatively expensive as compared with plastic tubes now commonly used in centrifuges. The thinner walled plastic tubes can be pierced with a needle of the hypodermic type but such needles are subject to becoming plugged in so doing. By way of example, tubes of cellulose nitrate and cellulose butyrate are available in wall thicknesses ranging from ten to fifteen thousandths of an inch. The walls of polypropylene and polycarbonate tubes are considerably thicker, forty thousandths of an inch, for example. Special needles are required with said thicker walled tubes.

The objective of the present inventions is to provide apparatus in which a specimen tube of any material that can have a hole punctured in its bottom without fracturing can be mounted, its bottom pierced by a needle, and the flow of the gradients from the specimen-containing tube to the collection tubes controlled easily and accurately.

In accordance with the invention, this objective is attained with apparatus utilizing, at least when set up for use, a specimen container including an open-ended tube portion for a liquid separated into gradients and a closure portion for its open end provided with a conduit in communication with the interior of the tube portion. The apparatus includes means to support the container in a vertical position, bottom end downwardly, a conduit including a tubular pointed needle of a stock sufficiently rigid to withstand pressures required to force the needle through the bottom of the tube portion, and means supporting the needle in a vertical position with its puncturing point disposed upwardly towards the bottom of the

tube portion and in axial alignment therewith with the needle. The apparatus also includes means to effect relative movement between the two supporting means to effect the puncturing of the bottom of the tube portion by the needle. One of the conduits is an outlet conduit and has a discharge end and the other conduit is an inlet conduit and means are provided to control the flow of fluid from the specimen container to the collecting tubes.

Another objective is to provide such apparatus with a seal against leakage, the seal being pierced by the needle and on the relative movement between the supporting means to effect puncturing of the bottom of the specimen-containing tube, the bottom being seated against the seal.

Another objective of the invention is to provide a conveyor for the collecting tubes movable relative to the station defined by the discharge end of the outlet conduit.

Another objective of the invention is to provide apparatus including a base and an upright with the conveyor being a turntable rotatably supported thereby and with the container and needle supporting means mounted on the upright.

A further objective of the invention is to provide the apparatus with a refrigerant chamber and additional important objectives include means by which the chamber and the tube supporting means are easily adapted to specimen containers of different dimensions.

Yet another objective of the invention is the provision of a needle ensuring ready penetration of the bottom of the specimen containing tube even when thick walled.

In the accompanying drawings, there are shown embodiments of the invention illustrative of these and other of its objectives, novel features, and advantages.

In the drawings:

FIGURE 1 is a partly sectioned side view of apparatus in accordance with one embodiment of the invention,

FIGURE 2 is a section taken approximately along the indicated lines 2—2 of FIGURE 1,

FIGURE 3 is a side elevational view of a tube piercing needle,

FIGURE 4 is a fragmentary view of the tube piercing end of the needle showing the inlet,

FIGURE 5 is a like view of the tube piercing end turned 180° from its FIGURE 4 position,

FIGURE 6 is a section taken approximately along the indicated lines 6—6 of FIGURE 5,

FIGURE 7 is a fragmentary view of the apparatus with the tube holder and refrigerant chamber adapted for a differently dimensioned tube,

FIGURE 8 is a fragmentary section, on a substantially increased scale, of the lower end of a tube end of the tube-puncturing needle illustrating means for controlling the relationship of the needle inlet with reference to the interior of a tube,

FIGURE 9 is a section taken approximately along the indicated lines 9—9 of FIGURE 1, and

FIGURE 10 is a section taken approximately along the indicated lines 10—10 of FIGURE 1.

The apparatus illustrated by FIGURES 1—9 of the drawings consists of a base 15 having an upwardly opening socket 16 to receive the lower end of the post or upright 17 and provided with a set screw 18 for detachably securing it therein. The post 17 has a collar 19 in support of the generally indicated turntable 20.

The turntable 20 is shown as consisting of an upper disc 21, a bottom disc 22, and an intermediate disc 23. The discs have central apertures freely receiving the post 17, the apertures being designated by the suffix addition "A" to the appropriate disc-identifying reference numeral. The discs are interconnected in vertically spaced

relationship as by bolts 24 extending downwardly through the discs 21, 22, and 23. Each bolt 24 extends through tubular spacers 25 and 26, the spacers 25 being between the discs 21 and 23 and the spacers 26 being between the discs 22 and 23.

The discs 21 and 23 have, adjacent their peripheries, a series of uniformly spaced, vertically aligned holes 21B and 23B, respectively, dimensioned to slidably receive collecting tubes 27 with their bottom ends being supported by the bottom disc 22.

A collar 28, above the turntable 20 and secured to the post 17, as by a set screw 29 is provided with a radial arm 30 having an upturned end 31 provided with a holder 32 for the outlet 33 to which one end of the drain tube 34 is connected. On the undersurface of the arm 30, there is a downwardly opening cup 35 retaining a ball 36 backed by a spring 37. The disc 21 has a series of holes 21C, one for each tube-receiving hole 21B and in radial alignment therewith with the resulting detent action permitting the turntable to be indexed relative to the station established by the discharge end of the outlet 33.

Spaced above the collar 28, there is a collar 38 rotatably supporting a transverse shaft 29 provided with a shaft-turning handle 40 and a pinion 41 meshing with the vertical rack 42 anchored in a slot 43 in the post 17. The post 17 is provided with a ring 44 below the slot 43 providing a stop against which the collar 38 is seated by a spring 45 backed by the anchor ring 46 fixed to the post 17. The collar 38 has a set screw 47, see FIGURE 10, by which it may be locked to the post 17 in any elevated position, within the limits permitted by the rack and pinion connections, against the returning action of the spring 45. The collar 38 also has a radially disposed arm 48 provided with an upwardly opening socket 49 provided with a set screw 50 and a concentric downwardly opening passage 51.

A needle, generally indicated at 52, is shown in FIGURES 3-6 and 10, as consisting of a cannula 53 provided with a centrally located hub 54. The bottom piercing end of the cannula 53 is provided with a point 55 of the type so positioning the inlet 56 that it opens laterally. The piercing end also has two flattened zones 55A providing a V-shaped ridge terminating in the point 55. In addition, the cannula 53 is shown as having a tapered portion 57 so reducing the diameter of the cannula that the maximum width, thereof, as measured across the inlet, is less than the diameter of the main part of the cannula. While other types of needles may be used, particularly with the thinner-walled tubes and with tubes having rubber seals, a needle of the type just described has the advantages of enabling the bottoms of thicker-walled tubes to be readily pierced and of cutting a flap in them and other tubes, as it pierces the tube bottom, and pushing that flap away from the needle point in a zone opposite its inlet 56. Such a flap is indicated at F in FIGURE 7.

The needle 52 is supported in the socket 49, pointed end upwardly and with its other end extending downwardly through the passage 50 with the other end of the drain tube 34 connected thereto. The set screw 50 serves to lock the hub securely in the socket 49 and the needle 52 pierces a seal 59 shown as seated in the upper end thereof.

Adjacent the upper end of the post 17 there is a collar 60 detachably locked thereto as by the set screw 61. The collar 60 has a radial arm 62 having clamping jaws 62A adapted to be drawn together by the screw 63. The jaws 62A are shown in FIGURE 1 as supporting a holder 64 having a downwardly opening socket 65 having a seal 66 seated therein and a concentric upwardly opening passage 67 to which the conduit 68 is attached and adapted to be opened and closed as by the clamp 69. The socket 65 is dimensioned to snugly receive and support the open end portion of a specimen containing

tube 70 with its lower end positioned above the needle 52 but axially aligned therewith.

With a specimen-containing tube 70 and the needle 62 thus supported, and with the clamp 69 closed, the handle 40 is swung by the technician thereby to raise the needle 62 until it pierces the bottom of the tube 70 and the tube bottom is seated on the seal 59. The desired fraction can then be delivered to the collecting tube 27 at the collecting station by releasing the clamp 69, the flow rate being slow, usually by drops.

With the apparatus thus described, it will be assumed that the desired fraction is determined by drop-counting and after that amount is delivered, the clamp is then engaged and the turntable 20 is indexed to bring another collecting tube 27 into the station.

It will be appreciated that the specimen containing tubes vary as to their dimensions. Their outside diameter, their length, or both may vary. While the supporting means therefor are vertically adjustable, it should be noted that it is a common requirement that specimen-containing tubes be maintained at or below a certain temperature.

For that reason, there is shown a collar 71 locked to the post 17 as by a set screw 72. The collar 71 includes a refrigerant holder 73 having a threaded and internally shouldered opening 74 in its bottom wall. The opening 74 is dimensioned and threaded to receive the generally indicated tube receiver 75 and a seal S. The receiver has a base 76 provided with a sleeve 77 and having an opening 78 concentrically thereof. The sleeve 77 is dimensioned to receive a major part of the length of the tube 70 when supported by the base 76 with its bottom exposed through the opening 78 for puncturing engagement by the needle 62. It will be apparent from FIGURE 1 that the distance between the socket 65 and the end of the sleeve 77 is desirably small.

With a tube of a smaller outside diameter, the tube 70A, for example, see FIGURE 7, it may be assumed that its length will be different than that of the tube 70. The tube 70A cannot, accordingly, be properly supported in the apparatus as thus far disclosed. The receiver 75 is accordingly removed and replaced by the receiver 75A which may be of the same construction as the receiver 75 and its corresponding parts are, accordingly, distinguished by the suffix addition "A." The sleeve 77A has its inside diameter such as to snugly fit the tube 70A and preferably has its outside diameter reduced so as to avoid undue thickness for the sake of thermal conductivity. The tube 70A is also shorter so that it is necessary to replace the holder 64 with a holder 64A which may be of the same construction and has its corresponding parts distinguished by the suffix addition "A," the socket 65A being of a correspondingly smaller inside diameter and the holder being proportioned to protrude downwardly a greater distance thereby to overlie the open end of the tube 70A close to the upper end of the sleeve 77A.

It will also be noted that the container and refrigerant holding means are removable from the post 17 and are adapted to have their positions thereon vertically adjusted as desired or required.

It will also be noted that it will often be necessary or desirable to maintain the temperature of the tubes 27 at or below a predetermined temperature during the period they are carried by the turntable 20. For that reason, see FIGURE 1, a refrigerant chamber 79 is mounted on the upright 17 to be supported by the socket 16 with the turntable 20 free to rotate within it.

It should also be noted that specimen containers of the same dimensions may present additional problems. A container 70B of the same general dimensions as the container 70 might have, by way of example, a lesser wall thickness or it might be that it was desirable to have the needle 62 extend to a greater or lesser extent therein. For such reasons, it may be desirable to provide

the seal 59 with additional layers 59A, the number of which may be increased or decreased to vary needle penetration as desired.

While the apparatus affords substantial advantages whether the delivery to each collecting container 27 is determined by the manual counting of the number of drops or by the technician timing the flow interval, the apparatus is adapted to a wide range of control bases including automatic operation with automatic operator including the stepping of the turntable, the control of the volume, and the control of the displacement fluid, or any of them. In this connection, it will be apparent that with a replacement liquid delivered by a precision pump, the tube puncturing needle may be in the inlet conduit with the outlet conduit in communication with the interior of the specimen tube via its upper end.

By these or like means, the apparatus may be made operable to control the accurate delivery of fractions from a specimen container successively to a series of collecting tubes.

I claim:

1. A tube-puncturing device for use with a specimen container in the form of an open-ended tube, at least the bottom portion of said tube being capable of being punctured by a needle, said apparatus comprising a vertical support, means detachably supporting said tube, bottom end downwardly exposed and with the tube axis vertical, said means including a seat member for centering said tube, a backing member for holding the open end of said tube against said seat, one of said members including a portion shaped and dimensioned to center and hold vertically a portion of a seated tube that is above said seat, and adjustable means operable to enable one of said members to be moved in a vertical direction towards the other member to provide holding engagement of said backing member with the open end of said seated tube, a conduit including a tubular, pointed needle below said seat member and of stock sufficiently rigid to withstand pressures required to force the needle through the bottom of the tube, means supporting said needle with the needle axis vertical and in alignment with the tube axis, both of said supporting means being mounted on said support, and means to effect relative vertical movement between said two supporting means to effect the puncturing of said tube bottom by said needle.

2. The tube-puncturing device of claim 1 in which the means effecting vertical movement between the two supporting means includes a vertical portion of the support in the form of a rack and the needle supporting means includes a pinion meshing with the rack portion.

3. The tube-puncturing device of claim 2 and a spring yieldably opposing relative movement of the needle supporting means towards the tube supporting means and means to lock said needle supporting means to the support against the action of the spring.

4. The tube-puncturing device of claim 1 in which the support is a post and a turntable is axially mounted on said post and is provided with a plurality of equally spaced means for holding fraction collecting tubes in an upwardly opening position, said conduit being positioned to discharge into appropriate ones of the fraction collecting tubes as the turntable is turned.

5. The tube-puncturing device of claim 4 and a chamber for a refrigerant in which the turntable is located.

6. The tube-puncturing device of claim 1 in which there is an annular refrigerant chamber, and the member centering and holding vertical a portion of a seated tube is the inner wall of the refrigerant chamber.

7. The tube-puncturing device of claim 1 in which the seat member includes a threaded part and the member centering and holding vertical the seated tube is threaded into the threaded seat part.

8. The tube-puncturing device of claim 1 in which the backing member is a closure including an inlet conduit in communication with the interior of the tube.

9. The tube-puncturing device of claim 1 in which the backing member is the member centering the tube and holding it vertical.

10. The tube-puncturing device of claim 9 in which the backing member has a downwardly opening socket dimensioned to snugly receive the open end of the seated tube.

11. The tube-puncturing device of claim 9 in which the backing member includes a tube-engaging adapter part and a supporting part having an aperture detachably receiving the adapter part, one of said parts including an annular shoulder holding the adapter part against upward movement.

12. The tube-puncturing device of claim 1 in which the backing member is the vertically adjustable member.

13. A tube-puncturing device for use with a specimen container in the form of an open-ended tube, at least the bottom portion of said tube being capable of being punctured by a needle, said device comprising means to support said tube, bottom end downwardly and exposed and with the tube axis vertical, a conduit including a needle, said needle being a cannula comprising a main portion and a tube-piercing portion tapering inwardly from its junction with said main portion and including a point whose apex is within the cylindrical boundary defined by the main cannula portion and which has a laterally opening inlet between said apex and said junction, means supporting said needle with its point upwardly and with the needle in axial alignment with the axis of a tube in said supporting means and means to effect relative vertical movement between the tube supporting means and the needle supporting means to effect the puncturing of the tube bottom by said needle and the seating of its tapered portion below said opening against said tube bottom.

14. The tube-puncturing device of claim 13 and means to adjust the position of the tube supporting means relative to the needle supporting means independently of the means effective relative movement therebetween.
